SHOE TREE

William H. Doherty, Elmhurst, N. Y.

Application January 11, 1949, Serial No. 70,191

15 Claims. (Cl. 12—128.3)

1

This invention relates to new and useful improvements in shoe trees and lasts.

An object of the invention is to provide a simple, efficient, durable and easily operated device to be inserted into shoes as a shoe tree or to be used within a shoe upper as a last during the process of applying soles to the uppers.

In brief and general terms the invention concerns a shoe tree which includes a sole plate upon which is disposed a toe piece with laterally movable former portions on the sole plate, a wedge piece movable on the sole plate and disposed between the former portions, with means for advancing and retracting the wedge piece, and with the former portions preferably resiliently supported above the sole plate from the toe piece.

The invention further includes a counter piece with which is associated a clamping piece, an adjustable connection between the wedge piece and the rear of the shoe preferably connected to the clamping piece and with, in most forms, a flexible band connected to the toe piece and extending between the clamping piece and the counter piece, said band adapted to be clamped firmly in position in one instance at least by the reaction of the adjustable device on the clamping piece.

Further details of construction and operation will appear evident from the following description especially when taken in conjunction with the drawings:

The present preferred forms which the invention may assume are illustrated in the drawings, of which,

Fig. 1 is a longitudinal vertical section through a preferred form of the invention;

Fig. 2 is a horizontal section taken on the line 2—2 of Fig. 1;

Fig. 3 is a longitudinal vertical section through a modified form of the invention;

Fig. 4 is a side elevation of still another modified form of the invention; and,

Fig. 5 is a vertical cross section taken on the line 5—5 of Fig. 4.

Referring now merely to the detailed description of the forms of the invention shown in the drawings, it will be seen that with regard to the form shown in Figs. 1 and 2, there is shown a shoe having an inner sole 10, toe 11, vamp 12, sides 13, and counter 14. Disposable in the forward portion of the shoe on the insole 10 is a stiff metal sole plate 15 having a longitudinal slot 16 and an up-turned rear portion 17 also provided with a longitudinal slot 18 and which rises above the top of the side walls 13.

5 Fixed to the forward portion of the sole plate 15 is a toe piece 19. Disposed on top of the plate 15 and along the vamp sides of the shoe are laterally movable former portions 20 and 21 slidably supported above the plate 15 by means of their connection to ends of the resilient strips 22 fixed to the toe piece 19 as shown. This permits the former portions to be spread laterally above the plate 15. This spreading action is effected 10 by means of a wedge or spreader piece 23 which is slidable along the top of the plate 15 and has sloping side walls 24 lying parallel to similarly sloped walls 25 on the former portions 20 and 21. The wedge piece 23 is provided with a headed stem 26 thereon extending down through slot 16 in the sole plate 15. The upper surface of the wedge piece 23 is provided with a series of holes 27 along its longitudinal median line.

15 Disposed in the rear of the shoe at the counter 20 area is a counter piece 28 having a vertical slot 29 in its forward face in which is disposed pivotally an adjustable clamping piece 30 pivoted on a pin 31. As shown in Fig. 1 the adjacent faces of the slot 29 and the clamping piece 30 are 25 spaced somewhat from each other but are similarly formed in a smooth curve as shown, thus providing a curved passageway therebetween for a metal strip of preferably spring steel 32 which especially along its portion lying in the passage 30 way between the slot 29 and the clamping piece 30 has a longitudinal slot 33 therein. The forward end of the strip 32 is connected to the stem 26 on the wedge piece 23.

20 The wedge piece 23 is moved back and forth 35 on the plate 15 by means of a screw threaded rod 34 the forward end of which 35 is bent down and is adapted to extend into one or the other of the holes 27. This rod extends through slot 18 in the plate portion 17 and through aligned bores 36 and 37 in the clamping piece 30 and the counter 40 piece 28 respectively. The slot 37 is much bigger than the rod to permit its axis to move laterally with respect thereto. The end of the rod 34 also extends through the slot 33 in the strip 32 previously mentioned. The rod 34 is provided with 45 an adjustable wing nut 38 which can be screwed along to bear against the adjacent face of the clamping piece 30 as shown in Fig. 1.

The upper end of the clamping piece 30 is bent horizontally and forwardly as shown in the form of spaced parallel arms one of which 39 is shown and these arms are embraced by a U-shaped clamp 40 movable into a desired position along a threaded stem 41 fastened in any suitable manner to the upper end of the vertical portion 17 of plate 15. An adjustable nut

42 can be adjusted to press down against the upper limb of the clamp 40 to force the clamp piece 30 tightly against the strip 32 as seen in Fig. 1, by pivoting it around its pivot pin 31 in a counterclockwise direction.

In the operation of this form of the foot former or tree, it is to be seen that with the nut 42 up to release the clamp on the arms 39 and with the nut 38 moved away from the face of the clamping piece 30, it is possible to roughly adjust the device in the shoe by grasping the vertical plate 17 in the hand and moving the plate 15 forward in the shoe as far as it will go. At the same time the counter piece 28 is disposed against the counter 14 of the shoe. The end 35 of the rod 34 is projected into a desired one of the holes 27 in the wedge piece 23 and then the nut 38 is tightened up to advance the wedge piece and thereby spread the former portions 20 and 21 against the sides of the toe of the shoe. When this adjustment has been achieved, the nut 42 is then screwed down to press on the clamp 40 and thereby on the arms 39, whereby the clamping piece 30 is pivoted around pin 31 to press against the strip 32 and hold it tightly against longitudinal movement. This will thereby present a strong, rigid unit to hold the shoe in proper shape either when used as an ordinary shoe tree or as a shoe last or former, for workmen who are putting on new soles.

In the form of the device shown in Figure 3, we still have the metal plate 15 disposed in the sole portion of the shoe on top of the insole 16 and we have the toe piece 19 and the former portions 20 and 21 as before supported by springs 22 from the toe piece 19. We also have the strip 32, in this case screwed directly to the bottom of the wedge piece 23 and passing through a slot in the slightly upturned rear end 43 of the plate 15. In this form, we also have the counter 14 and the counter piece 28 together with the curve clamping piece 30 in a slot 29, formed in the counter piece 28 there being a small passage between the adjacent curve surfaces of the clamping piece 30 and the slot 29 as shown, into which the strip 32 passes, this strip being provided as before, with a slot 33 therein. In this form the upper end of the strap 32 terminates within the slot 29 and the rear end of another strap 32' having a slot 33' therein, overlaps the end of the other strap 32 as shown in Fig. 3, and is bent over and extends forward under the vamp 44 of the shoe and is fixedly connected to the top of the toe piece 19 at 45, as shown.

The wedge piece 23 now is a plain block having sloping lateral walls shown in Figure 2, and provided with an upper rear slot 46 in which is pivoted on pin 47 a link 48 having a socket to receive a ball 49 on the end of screw shaft 50, passing through a bore 51 in the clamping piece 30 and through a larger bore 52 in the counter piece 28. The clamping piece 30 has a pin 53 disposed therein to engage the threads with the screw shaft 50. The end of the screw shaft 50 projects beyond the device, passes through an opening in a U-shaped plate 54 which passes across the back of the counter piece and the ends of the limbs of which are pivoted to the opposite sides of the counter piece 28. This construction will permit the angle of the screw shaft 50 to change slightly as the wedge piece is advanced or retracted. In this form, the reaction of the screw shaft against the clamping piece 30 as the wedge piece is moved forward, will cause the clamping of the strip 32. As the

angle of the shaft changes slightly, the clamping piece 30 can adjust its position in the slot 29.

In the form shown in Figs. 4 and 5, a further modification is illustrated in which the parts are somewhat the same as shown in Fig. 3 in that there is a toe piece 19, the insole 16 and the side forming members of which 21 is shown. It also has a screw shaft 50 swivelled as shown in Fig. 3, to the wedge piece 23 but in this form there is no metal strip such as 32. Instead there is a resilient rod 55 which extends through the toe piece 19, the wedge piece 23, through a hole in the upturned end 43 of the metal plate 15 and then rearwardly through a bore in the counter piece 28. This rod will tend to prevent the wedge piece from springing upwardly under pressure, and forms a means along which the wedge piece is guided. In this form, the counter piece 28 is associated with a clamping member 56 having a through bore somewhat similar to the bore 51 through which the screw shaft passes with a pin similar to 53 in Fig. 3 to effect the longitudinal motion of the screw shaft. This clamping member 56 is held somewhat loosely against the curved front face of the counter piece 28 by means of a U-shaped clip 56', the ends of which are driven into the front face of the counter piece 28 and which passes around the clamping piece 56 to hold it loosely in position while permitting a certain amount of movement between the curved face of this clamping piece and the similarly curved front face of the counter piece.

In order to shape the sides of the shoe while this form of device is being applied, I have provided a pair of plates 57 on opposite sides of the tree or last pivotally connected at 58 at their forward ends to the former portions 21 and 22, and having screw bolts 59 attached to their upper rear corners slidable in a slot 60 of a metal plate 61, pivoted at 62 to upturned portions 63 of a metal plate 64 which extends under the counter piece 28. When the device is put in a shoe, these plates 57, at their rear portions, are pressed down so that their lower edges lie along the bottom of the shoe and then nuts 65 on the screw bolts 59 can be tightened to hold them in this position but this tightening only takes place after the threaded shaft 50 has operated the wedge piece in the previously described manner to spread the former portions into their ultimate positions. After the parts are in their expanded position, a set screw 66 on top of the counter piece may be screwed down to engage the shaft 50 to hold it in its set angular position.

These various forms are all of a type which involves the expansion of former members against the sides of the forward portion of the shoe by the advancement of a wedge element and with the formed members resiliently supported from a toe piece. The construction of all three forms also involves the association of the toe piece with a counter piece by a connection such as the strap 32 or the rod 55, and the operation of the wedge piece through the intermediary of a screw means associated with the counter piece.

While the invention has been described in detail and with respect to the preferred form shown in the drawings, it is not to be limited to such details and forms since many changes and modifications may be made in the invention without departing from the spirit and scope of the invention in its broadest aspects. Hence, it is intended to cover any and all forms and modifications of the invention which may come within

the language or scope of any one or more of the appended claims.

What I claim as my invention, is:

1. A shoe tree which includes a sole plate, a toe piece on the sole plate, laterally movable former portions on the sole plate, and resilient means supporting the former portions from the toe piece.

2. A shoe tree which includes a sole plate, a toe piece on the sole plate, laterally movable former positions on the sole plate, springs supporting the former portions above the plate from the toe piece, a wedge piece disposed on the sole plate between the former portions, and means to move the wedge piece to and from said former portions, said springs adapted to restore the former portions to a normal position when disengaged from the wedge piece.

3. A shoe tree which includes a sole plate, a toe piece on the sole plate, laterally movable former portions on the sole plate, a wedge piece disposed on the sole plate between the former portions, a counter piece, an adjustable connection between the wedge piece and the counter piece, and resilient means supporting the former portions from the toe piece.

4. A shoe tree which includes a sole plate, a toe piece on the sole plate, laterally movable former portions on the sole plate, a wedge piece disposed on the sole plate between the former portions, a counter piece, a clamping piece pivoted to the counter piece with a passage formed between adjacent surfaces thereof, an adjustable connection between the wedge piece and the clamping piece, a flexible band connected to the wedge piece and disposed in said passage, and means for pivoting said clamping piece to press it against the band in the passage.

5. A shoe tree which includes a sole plate, a toe piece on the sole plate, laterally movable former portions resiliently supported from the toe piece above the sole plate, a wedge piece disposed on the sole plate between the former portions, a counter piece, a clamping piece pivoted to the counter piece with a passage formed between adjacent surfaces thereof, an adjustable connection between the wedge piece and the clamping piece, and a flexible band connected to the wedge piece and disposed in said passage, and means for pivoting said clamping piece to press it against the band in said passage.

6. A shoe tree which includes a sole plate, a toe piece on the sole plate, laterally movable former portions on the sole plate, a wedge piece disposed on the sole plate between the former portions, a counter piece, a clamping piece pivoted to the counter piece with a passage formed between adjacent surfaces thereof, an adjustable connection between the wedge piece and the clamping piece, a flexible band connected to the wedge piece and disposed in said passage, the rear of said sole plate being upturned, said clamping piece having a forwardly and horizontally extending arm, and means on said up-turned portion to engage said arm to pivot the clamping piece to press it against said band.

7. A shoe tree which includes a sole plate, a toe piece on the sole plate, laterally movable former portions resiliently supported from the toe piece above the sole plate, a wedge piece disposed on the sole plate between the former portions, a counter piece, a clamping piece pivoted to the counter piece with a passage formed between adjacent surfaces thereof, an adjustable connection between the wedge piece and the clamping piece.

a flexible band connected to the wedge piece and disposed in said passage, the rear of said sole plate being upturned, said clamping means having a forwardly and horizontally extending arm, and means on said up-turned portion to engage said arm to pivot the clamping piece to press it against the band.

8. A shoe tree which includes a sole plate, a toe piece on the sole plate, laterally movable former portions on the sole plate, resilient means supporting the former portions from the toe piece, a wedge piece disposed on the sole plate between the former portions, a counter piece, the wedge piece having a series of holes in its upper surface, and an adjustable connection associated at one end with said counter piece and at the other end disposed in one of said holes.

9. A shoe tree which includes a sole plate, a toe piece on the sole plate, laterally movable former portions on the sole plate, resilient means supporting the former portions from the toe piece, a wedge piece disposed on the sole plate between the former portions, a counter piece, the wedge piece having a series of holes in its upper surface, a clamping piece pivoted to said counter piece, an arm on the clamping piece and extending over the wedge piece, an upwardly extending portion at the rear of the sole plate, means on the upwardly-extending portion engaging the arm to pivot the clamping piece, a flexible band passing between the counter piece and the clamping piece and adapted to be gripped between them as the clamping piece is thus pivoted, one end of the band extending beneath the sole plate, and a pin connected to the end of the band and extending up through a slot in the sole plate and connected to the wedge piece.

10. A shoe tree which includes a sole plate, a toe piece on said toe plate, former portions resiliently supported from said toe plate for lateral movement above the sole plate, a wedge piece on the sole plate between said former portions, a counter piece, a clamping piece movably disposed in a slot in the counter piece, the counter piece and the clamping piece having aligned bores, a screw threaded shaft connected to the wedge piece and the clamping piece and extending through said bores, a flexible band connected to the wedge piece and extending between the clamping piece and the counter and another flexible band connected to the top of the toe piece and extending over the top of the clamping piece and lying between the clamping piece and the counter piece at its end, the reaction of the screw against the clamping piece as it advances the wedge piece toward the former portions whereby the ends of the flexible bands are clamped between the clamping piece and the counter piece.

11. A shoe tree which includes a sole plate, a toe piece on the sole plate, laterally movable former portions on the sole plate, a wedge piece disposed on the sole plate between the former portions, a counter piece, an adjustable connection between the wedge piece and the counter piece, and side shaping plates pivoted to the sides of the former portions and extending rearwardly along the side walls of the shoe.

12. A shoe tree which includes a sole plate, a toe piece on the sole plate, laterally movable former portions on the sole plate, a wedge piece disposed on the sole plate between the former portions, a counter piece, an adjustable connection between the wedge piece and the counter piece, and side shaping plates pivoted to the sides of the former portions and extending rearwardly

along the side walls of the shoe, a heel plate disposed under the counter piece, slotted metal link plates pivotally connected to the heel plate, and adjustable bolt and nut means associated with the slots in said plates and the upper rear ends of said side shaping plates.

13. A shoe tree which includes a sole plate, a toe piece on the sole plate, laterally movable former portions on the sole plate, a wedge piece disposed on the sole plate between the former portions, a counter piece, an adjustable connection between the wedge piece and the counter piece, and a flexible rod extending through the toe piece, the sole plate, the wedge piece and the counter piece to hold these parts in substantial alignment.

14. A shoe tree which includes a sole plate, a toe piece on the sole plate, laterally movable former portions on the sole plate, a wedge piece disposed on the sole plate between the former portions, a counter piece, an adjustable connection between the wedge piece and the counter piece, a flexible rod extending through the toe piece, the sole plate, the wedge piece and the

counter piece to hold these parts in substantial alignment, and side shaping plates pivoted to the sides of the former portions and extending rearwardly along the side walls of the shoe.

15. A shoe tree which includes a sole plate, a toe piece on the sole plate, laterally movable former portions on the sole plate, a wedge piece disposed on the sole plate between the former portions, a counter piece, an adjustable connection between the wedge piece and the counter piece, a flexible rod extending through the toe piece, the sole plate, the wedge piece and the counter piece to hold these parts in substantial alignment, side shaping plates pivoted to the sides of the former portions and extending rearwardly along the side walls of the shoe, a heel plate disposed under the counter piece, slotted metal link plates pivotally connected to the heel plate, and adjustable bolt and nut means associated with the slots in said link plates and the upper rear ends of said side shaping plates.
